CLAIM

The ornamental design for a fuel hopper, as shown and described.

DESCRIPTION

FIG. 1 is a front perspective view of the fuel hopper showing our new design.

FIG. 2 is a front elevation view of the fuel hopper in FIG. 1.

FIG. 3 is a rear elevation view of the fuel hopper in FIG. 1.

FIG. 4 is a right side view of the fuel hopper in FIG. 1.

FIG. 5 is a left side view of the fuel hopper in FIG. 1.

FIG. 6 is a top plan view of the fuel hopper in FIG. 1; and, FIG. 7 is a bottom plan view of the fuel hopper in FIG. 1. The broken lines in the drawings represent environment and form no part of the claimed design.

1 Claim, 7 Drawing Sheets
